FLUSHING DEVICE

George Schwibinger, Milwaukee, Wis., assignor to
 Rundle-Spence Mfg. Co., Milwaukee, Wis., a
 corporation of Wisconsin

Application June 27, 1932, Serial No. 619,513

4 Claims. (Cl. 4—250)

This invention relates to improvements in flushing devices and more particularly to seat operated devices for use in connection with water closets.

5 School buildings represent one of the most important fields for the sale of seat operated water closets because of the fact that this particular type of device insures flushing notwithstanding carelessness of the youthful user. The usual 10 water closet of this character is, however, objectionable because of the fact that the valve operating levers are so mounted as to be exposed to childish meddling and as a result frequent repairs are necessary.

15 It is one of the objects of the present invention to provide an improved flushing device of the seat operated type which is particularly adapted for school building use wherein the operating levers are so constructed and positioned 20 as to conceal the majority of the movable parts.

A more specific object of the invention is to provide a flushing device of the class described wherein the majority of the movable parts are arranged to be separated by a partition or wall 25 from the water closet itself, and wherein the front end of the lever connection with the seat is adapted to extend movably through said partition, said front end being connected to one 30 side of the seat in such a manner that meddling with this part can cause no damage to the movable parts on the other side of the partition.

35 A further object of the invention is to provide a flushing device embodying improved tripping mechanism for opening the valve which controls the flow of water to the closet.

A more specific object of the invention is to provide a flushing device embodying tripping mechanism which is particularly adapted for use in connection with a plunger operated flush valve.

40 A further object of the invention is to provide a flushing device wherein the tripping mechanism is formed with means adjustable to control the length of time during which the tripping member and the member being tripped are in 45 engagement with one another.

A further object of the invention is to provide a flushing device which is simple in construction, foolproof, and well adapted for the purpose described.

50 With the above and other objects in view, the invention consists of the improved flushing device and all its parts and combinations as set forth in the claims, and all equivalents thereof.

In the accompanying drawings illustrating one 55 complete embodiment of the preferred form of

the invention in which the same reference numerals designate the same parts in all of the views:

Fig. 1 is a perspective view showing a water closet embodying the improved device, parts being broken away;

Fig. 2 is a side elevational view thereof;

Fig. 3 is a front view showing the tripping mechanism and flush valve, parts being broken away and shown in section; and

Fig. 4 is a similar view showing the parts in a second position.

Referring more particularly to the drawings, the numeral 8 designates a water closet having a seat 9 hingedly mounted, as at 10. A lever arm 11 has its front end curved downwardly, as at 12, and in pivotal connection, as at 13, with the hinge pintle 14. A projection 15 in connection with the part 13 curves inwardly for engagement with a portion of the seat in such a manner that the seat 9 may be lifted to vertical position without affecting the lever arm 11, but in which downward pressure on the seat will cause engagement with the curved projection 15 and raising of the rear end of the lever 11. The said lever extends through a slot 16 formed in a wall or partition 17, and the rear end of the lever carries a weight 18 which normally tends to hold the seat in the full line position of Fig. 2.

The lever 11 extends loosely through the slotted opening 19 in a link 20, and said link has its upper end formed for threaded connection with a bolt 21. Said bolt has a bifurcated upper end portion 22 which embraces the lower end 90 of an actuating member 23, and which is pivotally connected thereto by means of a bolt 24. The lower portion of the actuating member 23 is squared and is slidable in a square aperture 25 formed in an angular projection 26 of a bracket 27. The said bracket has its upper end portion formed with a horizontally disposed tubular part 28 which is adapted for threaded connection by means of a nut 29 with a similar tubular part 30 projecting from the housing 31 100 for the flush valve.

The upper portion of the bracket 27 also carries a laterally projecting lug 31 having an opening therein through which the rod-shaped upper portion 32 of the actuating member is slideable. A coil spring 32' surrounding the rod 32 normally rests with its lower end on the lug 31. The upper end of the rod 32 is rigidly connected to a short, horizontally extending supporting bar 33. A tripping member 34 has its 110

upper end pivotally connected, as at 35, to the outer end of the bar 33. Said tripping member has an intermediate portion formed with a projection 36, the upper part of which is curved, as at 37, and the lower part of which is inclined, as at 38. The lower end of the tripping member 34 carries an eye 39 through which an adjustment bolt 40 is threaded, the inner end of said bolt being adapted to impinge against a side of the actuating member 23.

A valve operating lever 41 has its inner end pivotally connected, as at 42, to the upper portion of the bracket 27, and said lever has its outer end of angular formation, as at 43, so that when the tripping member 34 is moved upwardly from the position shown in Fig. 1 to the position shown in Fig. 3, it will not affect the lever 41, but that when said actuating member is moved downwardly it will engage the outer end 43 as shown in Fig. 4, and cause a downward pivoting of the lever 41.

The lever 41 has its lower side formed with a rounded projection 44 which is movable in the outer end of the tubular part 28 and which is engageable with the outer end of a plunger 45. Said plunger extends through the tubular portions 28 and 30 and through a bore 46 in the flush valve housing. The plunger 45 is inwardly movable against the tension of a coil spring 46 positioned around the plunger and within the tubular portions 28 and 30. Water is supplied to the flush valve by a pipe 47, and said valve is arranged to control the flow of said water under pressure from said pipe to the inlet pipe 48 for the water closet. The said flush valve is of standard construction and is caused to operate by the tilting of a rod 49, which rod is engaged by the inner end of the plunger 45.

The parts are normally in the position shown in Figs. 1 and 2, that is, the front portion of the seat is held in a slightly raised position by the counter-weight 18, the flush valve is closed, and the projection 36 of the tripping member is below the outer end of the valve operating lever 41. When pressure is exerted on the seat 9, this will overcome the counter-weight 18 and will cause an upward pivoting of the rear portion of the lever 11. Through the connections with the actuating member 23, the latter will be slidably moved from the lowered position shown in Fig. 1 to the raised position shown in Fig. 3, the projection 36 of the tripping member slipping past the operating lever 41 without affecting the latter. When pressure is removed from the seat, the counterweight 18 will cause a downward pull on the actuating member 23 and this will result in a downward movement of the tripping member 34 and in engagement of the lower angular face 38 of the projection 36 with the upper angular face of the outer end of the valve operating lever 41, as shown in Fig. 4. This will result in a downward pivoting of the lever 41, and through the rounded projection 44 on the latter an inward pressure will be exerted on the plunger 45 against the tension of the coil spring 46 to cause tilting of the rod 49 of the flush valve and opening of said valve. When the valve operating lever 41 has been pivoted downwardly to a certain point, the angular face 38 of the projection 36 will slide off of the outer end of said lever, and the parts will return to the position shown in Fig. 1, the coil spring 32 serving to absorb any shock. The length of time during which the tripping member is in engagement with the valve operating lever may be controlled through the ad-

justment bolt 40, that is, the said bolt threaded inwardly to shorten the length of time of engagement.

It is to be emphasized that the lever arm 11 is in connection with one side of the rear of the seat so that the central projection 50 of the water closet can be avoided to permit the lever arm to be extended directly through the partition 17. Thus the only exposed operating part is the short length of the lever arm 11 in front of the partition, and this part is so constructed that any meddling with it cannot possibly cause injury to the operating parts on the other side of the partition.

It is further to be pointed out that the improved tripping mechanism provides for a positive and fool-proof engagement with the valve operating lever 41, and that this construction while not limited to use in connection with flush valves, is particularly well adapted for use in connection with this type of valve wherein there is a horizontally slideable plunger such as the plunger 46.

Although only one form of the invention has been shown and described, it is obvious that various modifications and changes may be made, and that all of such changes are contemplated as may come within the scope of the claims.

What I claim is:

1. A flushing device for a water closet having a movable seat and having a valve for controlling the flow of water, comprising a pivotally mounted valve operating lever, a vertically slideable actuating member, a tripping member pivotally suspended from said actuating member, said tripping member being formed with means shaped to engage said valve operating lever for a predetermined length of time during downward movement of the tripping member and actuating member, weighted means connected between said water closet seat and actuating member for causing slideable movement of the latter upon movement of the seat, and means for cushioning the downward movement of said actuating member caused by the weighted means.

2. A flushing device for a water closet having a movable seat and having a valve for controlling the flow of water, comprising a pivotally mounted valve operating lever, a vertically slideable actuating member, a tripping member pivotally suspended from said actuating member, said tripping member being formed with means shaped to engage said valve operating lever for a predetermined length of time during downward movement of the tripping member and actuating member, means connected between said water closet seat and actuating member for causing slideable movement of the latter upon movement of the seat, and means carried by the tripping member for adjusting the normal position of said tripping member to vary the length of time of engagement with the valve operating lever during downward movement of the tripping member.

3. A flushing device for a water closet having a movable seat and having a valve for controlling the flow of water, comprising a pivotally mounted valve operating lever, a vertically slideable actuating member, a tripping member pivotally suspended from said actuating member, said tripping member being formed with means shaped to engage said valve operating lever for a predetermined length of time during downward movement of the tripping member and actuating member, means connected between said water closet seat and actuating member for causing slideable movement of the latter upon movement

of the seat, and a set screw carried by the lower end of the tripping member for adjusting the normal position of said tripping member to vary the length of time of engagement with the valve operating lever during downward movement of the tripping member.

4. A flushing device for a water closet having a flush valve for controlling the flow of water, comprising a bracket disposed adjacent said flush

valve, a union connection between said bracket and flush valve, a valve operating plunger horizontally slideable through said union connection, a lever pivoted to said bracket for movement in a vertical plane and having an enlarged portion engageable with said plunger, lever actuating means vertically slideably carried by said bracket, and means for moving said lever actuating means.
